UNITED STATES PATENT OFFICE.

GORDON FOX, OF CHICAGO, ILLINOIS, ASSIGNOR TO FREYN ENGINEERING COMPANY,
OF CHICAGO, ILLINOIS, A CORPORATION OF MAINE.

HEATING MEANS FOR ROLLS.

Application filed April 30, 1925. Serial No. 26,904.

The present invention relates to heating means for rolls.

More particularly the present invention relates to means for heating rolls such as are used in sheet mills. In cold rolling sheets for finishing purposes it is difficult to retain the rolls in perfect shape due to the fact that differences in friction at the bearings lead to variations in temperature. Moreover, differences in the work done upon the sheets due to variation of thickness causes the surface of the rolls to heat up more at one point than at other points. The differences in temperature referred to tend to cause variations in expansion of the rolls which tend to destroy parallelism of the roll contours. In order to compensate for such variations in temperature it has been proposed to apply a gas flame at portions of the roll which require heat treatment. Such practice is open to considerable objection, however, certain difficulties being due to the difficulty in properly controlling the gas flame and restricting said flame to the desired zone. Difficulty has also been encountered in the rolling of sheets by the continuous process, in maintaining the proper contour of the roll and in maintaining the proper temperature. This difficulty has been largely responsible for the failure of attempts to roll sheets by the continuous process.

An object of the present invention is to provide roll heating means which may be applied to the rolls of a mill without interfering with the operation of said rolls and which will permit efficient control of the temperature in said rolls.

A further object is to provide heating means for rolls which permit ready control of the heat applied at different portions of the rolls disposed longitudinally of said rolls.

A further object is to provide a roll heating means of improved type to meet the needs for commercial operation.

Further objects will appear as the description proceeds.

Referring to the drawings—

Figure 1 is a sectional view of a sheet mill taken transversely of said mill and illustrating one embodiment of the present invention;

Figure 2 is a view in side elevation of the structure shown in Figure 1; and

Figure 3 is a diagrammatic view illus-

trating an electric circuit applicable to the present invention.

The numerals 1—1 indicate a pair of rolls which are rotatably carried in parallel relationship with one another by the supporting members 2—2. Said supporting members are provided with adjusting means (not illustrated) whereby the distance between the axes of the rolls 1—1 may be varied as desired. The supporting members 2—2 are slidably mounted upon the bed plates 3—3, whereby said supporting members may be disposed at the proper distance for taking rolls 1—1 of different lengths.

The present invention contemplates heating members 4 and 5 mounted in heat conducting relationship with the upper and lower rolls, respectively. Said heaters are arranged circumferentially of said rolls, but are held in spaced relationship therewith so as not to interfere with the rotation of said rolls. In order that interference may not be had with the rolling operation the throat between the rolls is left unobstructed, and for this purpose the heating member 4 is located above the upper roll 1 and the heating member 5 is located below the lower roll 1. According to the structure illustrated, heating members are provided having longitudinal dimensions almost as long as the rolls to be heated, though the invention is not limited to any particular ratio between the length of the rolls and the length of the heating members. The heating members may be materially shorter than the rolls, and the present invention contemplates means whereby the heating members may be moved longitudinally of said rolls, whereby to apply heat selectively at different regions disposed longitudinally of the rolls.

The heating members 4 and 5 are arranged in the form of sectors and are somewhat flexible. Said heaters are adjustably mounted, in order that a small air gap may be maintained with compensation for rolls of different diameters. Said heaters may contain lagging or heat insulating material to prevent excessive loss through heat radiation. On the inner surfaces of the sector-shaped heaters are located a plurality of electric heating elements 6—6 of the strip type, which heating elements have their long dimensions arranged circumferentially of the rolls. The circuit of each of the heating

- elements is independently controllable, independent switch members 7-7 being provided for such independent control. By reference to Figure 3 it will be noted that the switches 5 7-7 control the connection of the heating elements 6-6 across the mains 8-8. It will be noted that zone control may be readily had by individually controlling the electric circuits of the heating elements 6-6.
- 10 Each of the heating members 4 and 5 may have a sufficient number of heating elements 6-6 on the inner side thereof to apply heat when required to practically the entire length of roll, from bearing to bearing. If preferred, relatively short heating members 4 and 5 may be provided, and said heating members may be moved longitudinally of the rolls, whereby the heat may be applied locally to the region desired. In order to 15 make it possible to move the heating elements 4 and 5 longitudinally of the rolls, supporting means may be provided which slidably carry said heating elements 4 and 5. Carried at the upper regions of the supports 20 2-2 are the bars 9-9, which bars are provided with the collars 10-10, which may be adjustably connected to said bars 9-9 (as, for example, by set screws 10'-10') at preferred regions longitudinally of said bars 25 9-9. Said collars 10-10 are provided with screw-threaded studs 11-11, which adjustably support the cross bearers 12-12. Each of said cross bearers 12-12 is provided with the downwardly extending arms 13-18, 30 which may be braced adjacent to their lower extremities by the cross brace 14. The numerals 15-15 indicate supporting members carried at the lower extremities of the arms 13-13, which supporting members 15-15 35 are connected to the sides of the heating member 4. The middle portion of the heating member 4 may be supported by the cross braces 14-14. Terminals 16-16 carried by the heating member 4 provide convenient 40 means for connecting the various elements 6-6 in circuit. The bed plates 3-3 are provided with upstanding screw-threaded studs 17-17, which are adjustable longitudinally of said bed plates 3-3 and which 45 50 adjustably support cross bearers 18. Said cross bearers 18 are provided with the upstanding arms 19-19 carrying the supporting members 20-20 for attachment to the two sides of the heating member 5. The 55 heating member 5 is provided with the terminals 16-16, which may be identical with those referred to above in connection with the heating member 4. Said screw-threaded studs 17-17 may be adjustable longitudinally 60 65 of the bed plates 3-3 (by means not illustrated), whereby the cross bearers 18-18 may be adjusted longitudinally of the rolls. 70 By reason of the fact that the heating members 4 and 5 are disposed in positions 65 such that they do not interfere with the

throat between the rolls 1-1, and by reason of the fact that said heating members are held in spaced relationship with said rolls, the temperature of said rolls may be controlled during rolling operations. Inasmuch as the heating elements 6-6, which are spaced longitudinally of the rolls, are independently controllable, any desired localization of the heat may be readily accomplished. Moreover, if it is preferred to use relatively short heating members 4 and 5, said heating members may be adjusted longitudinally of the rolls, whereby to localize their application of heat, to the end that the desired distribution of heat may be had.

Though a preferred embodiment of the present invention has been described in detail, it will be clear that many modifications will occur to those skilled in the art. It is intended to cover all such modifications that fall within the scope of the appended claims.

What is claimed is:

1. In combination, a pair of rolls and flexible heating members cooperatively associated therewith, said heating members including a plurality of electrical heating strips having their long dimensions arranged circumferentially of said rolls and being disposed in spaced relationship longitudinally of said rolls, and means for independently controlling the energization of said strips.

2. In combination, a pair of rolls mounted in parallel relationship with one another and forming a pass for the reception of material to be operated upon, each of said rolls having a flexible heater associated therewith, said heaters including members arranged circumferentially of said rolls but spaced therefrom, said heaters being disposed out of obstructing relationship with said pass, said heaters being provided with heating strips mounted in spaced relationship longitudinally of said rolls, said heating strips having their long dimensions arranged circumferentially of said rolls.

3. In combination, a pair of rolls mounted in parallel relationship with one another and forming a pass for the reception of material to be operated upon, each of said rolls having a flexible heater associated therewith, said heaters including members arranged circumferentially of said rolls but spaced therefrom, said heaters being disposed out of obstructing relationship with said pass, said heaters being provided with heating strips mounted in spaced relationship longitudinally of said rolls, said heating strips having their long dimensions arranged circumferentially of said rolls, said heating strips being provided with means for individually controlling the heating effects of said strips.

4. In combination, a pair of rolls mounted in parallel relationship with one another, each of said rolls having a heater associated

therewith, said heaters including members arranged circumferentially of said rolls but spaced therefrom, said heaters being disposed out of obstructing relationship with 5 the region between said rolls, said heaters being of materially less length than said rolls longitudinally of said rolls and being adjustably mounted longitudinally of said rolls, whereby the local application of heat 10 to different regions of said rolls may be readily accomplished.

5. In combination, a pair of rolls forming a pass for the reception of material to be operated upon, means for rotatably supporting 15 said rolls, heaters arranged in circumferential relationship with said rolls but spaced therefrom, said heaters being out of obstructing relationship with said pass, and means for adjustably carrying said heaters 20 whereby the spaced relationship between said heaters and said rolls may be controlled.

6. In combination, a pair of rolls, a heater mounted in proximity to one of said rolls but in spaced relationship therewith, and 25 means for supporting said heater, said supporting means being adjustable, whereby said heater may be secured at selective positions longitudinally of said rolls, said heater being disposed out of obstructing relationship 30 with the pass between said rolls, whereby the temperature of the rolls may be con-

trolled during the passage of work between said rolls.

5. In combination, a pair of rolls forming mounted in proximity to one of said rolls but 35 in spaced relationship therewith, and means for supporting said heater, said supporting means being adjustable, whereby said heater may be secured at selective positions longitudinally of said rolls, said heater being provided with heating strips mounted in spaced relationship longitudinally of said rolls, said heating strips having their long dimensions arranged circumferentially of said rolls.

8. In combination, a pair of rolls, a heater 40 mounted in proximity to one of said rolls but in spaced relationship therewith, and means for supporting said heater, said supporting means being adjustable, whereby said heater may be secured at selective positions 45 longitudinally of said rolls, said heater being provided with heating strips mounted in spaced relationship longitudinally of said rolls, said heating strips having their long dimensions arranged circumferentially of said rolls, said heating strips being provided with means for individually 50 controlling the heating effects of said strips.

Signed at Chicago, Illinois, this 24 day of April, 1925.

GORDON FOX.
